UNITED STATES PATENT OFFICE

103,110

DESIGN FOR A HEATER CASING OR SIMILAR ARTICLE

Peter Kilham, Santa Fe, N. Mex.

Application December 28, 1936, Serial No. 66,761

Term of patent 3½ years

To all whom it may concern:

Be it known that I, Peter Kilham, a citizen of the United States, residing at Santa Fe, in the county of Santa Fe, State of New Mexico, have invented a new, original, and ornamental Design for a Heater Casing or Similar Article, of which the following is a specification, reference being had to the accompanying drawing, forming a part thereof.

Fig. 1 is a perspective view of the heater casing or similar article showing my new design;

Fig. 2 is a front elevational view thereof;

Fig. 3 is a side elevational view;

Fig. 4 is a top plan view.

I claim:

The ornamental design for a heater casing or similar article, as shown.

PETER KILHAM.
